UNITED STATES PATENT OFFICE.

HENRY F. ELSHOFF, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

MOTOR-CONTROLLER.

No. 902,061.

Specification of Letters Patent.

Patented Oct. 27, 1908.

Application filed June 30, 1906. Serial No. 324,175.

To all whom it may concern:

Be it known that I, HENRY F. ELSHOFF, citizen of the United States, residing at Norwood, in the county of Hamilton and State 5 of Ohio, have invented certain new and useful Improvements in Motor-Controllers, of which the following is a full, clear, and exact specification.

My invention relates to multiple-voltage controllers.

In the patent to Dunn No. 797,271, granted Aug. 15, 1905, there is described a multiple-voltage controller in which a fixed resistance is temporarily cut into the armature circuit whenever the connections of the armature are changed from one set of mains to another. This resistance, now commonly known as a buffer resistance, serves to prevent excessive surges of current through 15 the armature when the impressed voltage thereon is either increased or decreased. In the Dunn patent this buffer resistance is inserted in circuit by raising one of the contact fingers from the controller drum, thereby 20 opening a short-circuit around the resistance. This is found to be unsatisfactory, because of the double movement of the drum and the finger and because there is only a point or line contact between the finger and its coöperating contact segment on the drum. The 25 present invention is intended to overcome this difficulty by having the buffer resistance inserted by a switch separate from the controller drum and its fingers, but operated by the drum 30 in its rotation.

In one aspect my invention comprises a controller consisting of a rotatable drum, and a switch arranged to be opened by said drum when the latter is moved between certain 40 positions, together with means which tends to close said switch and clockwork mechanism for retarding such closing.

In a more specific aspect my invention comprises, in combination, a multiple-voltage controller, a motor controlled thereby, a resistance in the armature circuit of said motor, a switch normally closed to short-circuit said resistance, said switch being separate from the controller drum but arranged to be 50 opened thereby to break said short-circuit whenever the armature connections are changed from one set of mains to another, and clockwork mechanism for retarding the closing movement of said switch.

Other features of my invention will appear 55 hereinafter.

Figure 1 is an elevation of a part of a controller embodying my invention, with the casing partly broken away in order to show the operating mechanism. Fig. 2 is a section 60 on the line 2—2 of Fig. 1. Fig. 3 is a diagrammatic view showing a development of the controller.

In the drawings, 31 is the controller drum operable by the usual handle 32. For the 65 sake of simplicity the connections of the controller drum here indicated are approximately the same as in the patent to Dunn aforesaid, but it is obvious that my invention is applicable to any other form of controller in which the voltage impressed on a motor armature is varied, and especially applicable to any form of multiple-voltage controller. The controller drum has contact segments 33 arranged to coöperate with the 75 contact fingers 34 to 39 inclusive, to connect the armature of motor M to different sets of the mains a, b, c and d. The drum also has a ring 40 and contact segments 41 arranged to coöperate with contact fingers 42 to 48 inclusive 80 to vary the resistance r in the field circuit of motor M.

Mounted on the shaft of the controller drum is a cam wheel 49, on the periphery of which rides a roller 50 carried by a lever 51. 85 The cam wheel 49 is shown developed in Fig. 3, but in order to show more clearly the operation of the device, it is shown as if its cam projections were on its upper surface instead of on its periphery. These cam projections are so located that they engage with and move roller 50 as the armature connections are being changed from one set of mains to another. Lever 51 is connected to a switch 52 by a rod 53 and link 54. A spring 95 55 tends to close the switch 52 and hold it closed. The bar 53 is provided with teeth 56 to form a rack, some of these teeth being cut away at 57 for a purpose hereinafter explained. Arranged to engage with the teeth 100 56 is a pinion 58. Integral with pinion 58 or otherwise firmly attached thereto is a ratchet wheel 59, whose coöperating pawl 60 is on a gear wheel 61 mounted to turn on the same axis as the wheels 58 and 59 but not fixed to 105 said wheels. The gear wheel 61 meshes with pinion 62, integral or otherwise attached to wheel 63, which coöperates with an escape-

ment 64. The escapement is provided with a weight 65 in order to slow its action. By reason of the pawl and ratchet 59 and 60 the train of gearing or clockwork mechanism 5 retards only the closing movement of the switch 52, its movement in the other direction being free or unretarded. The switch 52 when closed short-circuits a resistance R in the motor armature circuit, but when 10 opened breaks the short circuit to effectively include the resistance in said armature circuit.

When the controller is moved to change the armature connections from one set of 15 mains to another, the cam projections on cam wheel 49 move lever 51 to open the switch 52 and to include the resistance R in the motor armature circuit. During this 20 opening movement of the switch the teeth of rack 56 engage with those of pinion 58 to rotate the wheels 58 and 59. Because of the pawl and ratchet 59 and 60, the rest of the 25 clockwork mechanism remains stationary during this opening movement of the switch 52 and consequently does not retard such movement. As soon as the change of armature connections has been made, the spring 55 begins to expand to force the switch 52 toward closed position. This movement of 30 the switch, however, is at first retarded by the clockwork mechanism, the amount of this retardation depending upon the rapidity with which the escapement 64 can operate. When the switch is nearly closed, the teeth 35 56 pass out of engagement with pinion 58, bringing the cutaway portion of rod 53 adjacent said pinion. This allows the final closing movement of switch 52 to be unretarded so that a quick engagement of the 40 switch contacts may be secured. In the controller shown the resistance R is included in circuit when the controller passes between positions 7 and 8, 14 and 15, 18 and 19, 21 and 22, and 23 and 24, and also when it 45 passes to or from "off" position. Between the positions just mentioned the armature connections are changed from one set of mains to another. Between any other two adjacent positions the controller merely 50 varies the resistance r in the field circuit of the motor. This field resistance is arranged to be increased as the controller is moved forward between those adjacent positions where the armature connections are not 55 varied, thus increasing the speed of the motor, but to be cut out whenever the armature connections are varied, thus insuring a strong field whenever a higher voltage is impressed on the armature. If desired, in 60 stead of having some of the teeth on the rack 56 cut away, one or more of the teeth on pinion 58 may be cut away.

It is obvious that the part of the controller 65 which controls the field resistance may be varied as desired, and that the part which

controls the armature connections may be adapted to any multiple-voltage system and arranged if desired to reverse the armature current. These modifications as well as many others which readily occur to one skilled in the art may be made without departing from the spirit of my invention, and are intended to be covered by the following claims.

What I claim as new is:—

1. In a controller, a rotatable drum, a 75 switch biased toward closed position but arranged to be opened by said drum when the latter is moved between certain positions, and clockwork mechanism for retarding part of the closing movement of said switch only. 80

2. In a controller, a rotatable drum, a switch arranged to be opened by said drum when the latter is moved between certain positions, means which tends to close said switch, and clockwork mechanism arranged 85 to retard the first part of the closing movement of said switch but to allow the last part of the closing movement and all of the opening movement thereof to be unretarded.

3. A multiple-voltage controller, a motor 90 controlled thereby, a resistance in the armature circuit of said motor, a switch normally closed to short-circuit said resistance, said switch being separate from the controller drum but arranged to be opened thereby to 95 break said short-circuit whenever the armature connections are changed from one set of mains to another, and a train of gearing with an escapement for retarding the closing movement of said switch. 100

4. A multiple-voltage controller, a motor controlled thereby, a resistance for the armature circuit of said motor, a switch normally closed to short-circuit said resistance, said switch being separate from the controller 105 drum but arranged to be opened thereby to include said resistance in the armature circuit whenever the armature connections are changed from one set of mains to another, means tending to close said switch, and a 110 clockwork escapement for retarding such closure. 110

5. A multiple-voltage controller, a motor controlled thereby, a resistance for the armature circuit of said motor, a switch normally 115 closed to short-circuit said resistance, said switch being separate from the controller drum but arranged to be opened thereby to effectively include said resistance in the armature circuit whenever the armature connections are changed from one set of mains to another, means tending to close said switch, and clockwork mechanism for retarding such 120 closure, but arranged to allow a free opening movement of the switch. 125

6. A multiple-voltage controller, a motor controlled thereby, a resistance in the armature circuit of said motor, a switch normally closed to short-circuit said resistance, said switch being separate from the controller 120

drum but arranged to be operated thereby to open said short-circuit whenever the armature connections are changed from one set of mains to another, and clockwork mechanism for retarding part of the closing movement of said switch.

7. A multiple-voltage controller, a motor controlled thereby, a resistance in the armature circuit of said motor, a switch normally closed to short-circuit said resistance, said switch being separate from the controller drum but arranged to be operated thereby to open said short-circuit whenever the armature connections are changed from one set of mains to another, and clockwork mechanism for retarding the first part of the closing movement of said switch, but arranged to allow the last part of the closing movement and the whole of the opening movement of the switch to be unretarded.

8. A multiple-voltage controller, a motor controlled thereby, a resistance for the armature circuit of said motor, a switch normally closed to short-circuit said resistance, said switch being separate from the controller

drum but arranged to be opened thereby to include said resistance in the armature circuit whenever the armature connections are changed from one set of mains to another, means tending to close said switch, and clockwork mechanism for retarding such closure while allowing a free opening movement of the switch.

9. In a motor control system, multiple-voltage mains, a motor, a drum controller for connecting the motor armature to different sets of the mains, a resistance in the armature circuit of the motor, a switch separate from the controller and biased to closed position to short-circuit said resistance, means whereby a movement of the controller between certain positions opens said switch, and clockwork mechanism for retarding the closure of said switch.

In testimony whereof I affix my signature, in the presence of two witnesses.
